UNITED STATES PATENT OFFICE

2,613,361

TIED CLIP-ON BOW TIE

Julius A. Hirsch, Chicago, Ill., assignor to Cutter Cravat, Inc., a corporation of Illinois

Application November 30, 1951, Serial No. 259,266

1 Claim. (Cl. 2—151)

This invention relates to clip-on bow ties, that is, bow ties provided with clips for attaching the same to collars.

Most men like the appearance of bow ties, but the vast majority of them do not know how to tie bowknots on themselves or will not take the time or have the patience to do so. As a result, prefabricated simulated bow ties having attaching clips for attaching the same to shirt collars have been on the market for some time. They have not, however, made any great impression because of their extremely artificial and manufactured appearance. These simulated bow ties are readily detected even at a glance as being spurious and are not generally to the liking of the fastidious man.

The clip-on bow ties heretofore manufactured and sold have included two parts in addition to the attaching clip, one part having two wing portions that are folded upon themselves to form overlapping loops and ends and the other part taking the form of a band which is placed and sewed about the folded wing portions to simulate the central knot of the bow tie. The attaching clip is secured under the encircling band for the purpose of attaching the simulated bow tie to a shirt collar. Such a spurious bow tie does not have a true bowknot, the encircling band being a very poor simulation of the knot, it being usually too small and too regular in appearance. In fact, the entire tie has a too regular, artificial and manufactured appearance, and when worn it does not even appear to set right. Further, these ties when fabricated cannot be readily taken apart for cleaning, it being known that the bow ties becomes soiled quite rapidly.

The principal object of this invention is to provide an improved clip-on bow tie which eliminates all of the above faults and deficiencies of the simulated bow ties heretofore manufactured and sold, which is actually tied in a true bowknot so as to have the appearance and characteristics of a conventional hand tied bow tie, which may be pre-tied and provided with an attaching clip so that the bow tie may be readily clipped to a collar, which may be readily untied for cleaning purposes and then retied, which may be readily adjusted, which will not sag or twist, and which is simple and inexpensive to manufacture.

Briefly, the tied clip-on bow tie of this invention includes a single tie member having a pair of wing portions and a free central knot portion which is of less length than either of

5 the wing portions and just long enough to form the knot of a bowknot. An attaching clip is secured only to one of the wing portions. The single tie member is actually tied into a bowknot with the wing portions forming overlying loops and ends, with the free central knot portion encircling and forming a central knot about the wing portions and the attaching clip, and with the attaching clip exposed and extending 10 outwardly from each side of the central knot for clipping the tied bow tie to a collar. Such a tie is a true bow tie having a tied bowknot and yet may be quickly clipped on to a shirt collar. When in place on the person, it cannot be told from a conventional hand tied bow tie. It may be readily untied for cleaning purposes and then retied ready for wearing. Since the central knot portion forming the central 15 knot is free, this makes possible ready adjustment of the bow tie. Since the attaching clip is secured to one of the wing portions of the bow tie, sagging and twisting of the hand-tied bow tie with respect to the attaching clip is effectively prevented.

25 Other objects and advantages of this invention will become apparent to those skilled in the art upon reference to the accompanying specification, claim and drawings, in which:

Fig. 1 is a plan view of the rear side of the single tie member before the tie is tied and having an attaching clip secured to one of the wing portions thereof;

Fig. 2 is a front plan view of the single tie member illustrated in Fig. 1;

30 Figs. 3 to 6 illustrate the manner of tying the tie member into a bowknot for forming the tied bow tie;

Fig. 7 is a front view of the tied bow tie;

Fig. 8 is a rear view of the tied bow tie;

35 Fig. 9 is an enlarged top view of the tied bow tie.

In Figs. 1 and 2 there is illustrated a single tie member which may be formed in conventional manner out of suitable necktie fabric. It may be made in sheath form having the usual edge seams. It includes two wing portions 10 and 11 which are connected together by a relatively short free central knot portion 12 which is of less length than either of the wing portions 10 and 11 and which is just long enough to form the knot of a bowknot. The wing portion 10 on the rear side is provided with an attaching clip 13 which is of conventional construction and which is shown in more detail 40 in Figs. 1 and 9. The clip 13 includes a pair

of spring arms 14 which are inserted into holes in the wing portions 10 so as to be secured thereto. The attaching clip 13 also includes a pair of spring clips 15 and 16 which are adapted to grip the collar of a shirt.

In tying the single tie member into a bow-knot, the wing portion 10 having the clip 13 secured thereto is folded to form a loop 18 and an end 19, as illustrated in Fig. 3. The free central knot portion 12 is then circled over the wing portion 10, as illustrated in Fig. 4. The other wing portion 11 is then folded to form a loop 20 and an end 21, as illustrated in Fig. 5. The loop 20 is then inserted through the encircling free knot portion 12 to form a bowknot 22, as illustrated in Fig. 6. The bowknot 22 is then drawn up tight to form the completed tie, as illustrated in Figs. 7, 8 and 9. Thus, in tying the bowknot the wing portions 10 and 11 of the single tie member form overlying loops 18 and 20 and ends 19 and 21 and the short free central knot portion 12 encircles and forms a central knot 22 about the wing portions 10 and 11 and also about the attaching clip 13. The attaching clip 13 is exposed, being located on the rear face of the wing portion 10, and the spring clips 15 and 16 thereof extend outwardly from each side of the central knot 22 for clipping the tied bow tie to a collar of a shirt.

As is seen in Figs. 7, 8 and 9 the tied bow tie of this invention has the appearance of and cannot be distinguished from a conventional hand tied bow tie for the reason that the bow tie of this invention is a true bow tie having a tied bowknot. Yet, the bow tie of this invention may be quickly clipped onto a shirt collar. When and if the tie should become soiled, it may be quickly untied and cleaned and then retied ready for wearing. It may be readily adjusted and it will not sag or twist.

While the wings of the single tie member have

been shown in the form of bat wings, they may have any other desired shape. For example, the wings may be uniform in width and have squared ends instead of pointed ends. These wings may be wider than the free central knot portion or, if desired, they may be of the same width. The ultimate shape and size of the tied tie will determine the shape and size of the single tie member. While for purposes of illustration one form of this invention has been disclosed, other forms thereof may become apparent to those skilled in the art upon reference to this disclosure and, therefore, this invention is to be limited only by the scope of the appended claim.

I claim as my invention:

A tied clip-on bow tie comprising, a single tie member having a pair of wing portions and a free central knot portion of less length than either of the wing portions, and an attaching clip secured only to one of the wing portions, said single tie member being tied into a bowknot with the wing portions forming overlying loops and ends, with the free central knot portion encircling and forming a central knot about the wing portions and the attaching clip and with the attaching clip exposed and extending outwardly from each side of the central knot for clipping the tied bow tie to a collar.
